UNITED STATES PATENT OFFICE.

AARON W. GILMORE, OF TYLER, TEXAS.

RAIL-JOINT.

1,235,024.

Specification of Letters Patent. Patented July 31, 1917.

Application filed September 5, 1916. Serial No. 118,352.

To all whom it may concern:

Be it known that I, AARON W. GILMORE, citizen of the United States, residing at Tyler, in the county of Smith and State of Texas, have invented certain new and useful Improvements in Rail-Joints, of which the following is a specification.

Among the advantages claimed for my rail-joint, are; that it requires no extra plates or parts like the usual joint; that it is stronger and more durable; that it is more readily assembled and the parts are efficiently united; that only one bolt is required; that should the bolt become detached the joint will still remain connected; and that full provision is made for expansion and contraction.

In carrying out the invention the end of one rail is formed with a projecting base portion, an upstanding stud, and a projecting vertical web-lug; while the end of the adjacent rail is provided with an overhanging web and head portion formed with a socket adapted to receive the web-lug of the other rail, while the overhanging web rests on the projecting base portion of the other rail. The overhanging web has an elongated recess in its bottom receiving the stud and the lug have registering slots through which a connecting bolt is passed, the elongated recess and the slots permitting relative movement of the rails and caring for the expansion and contraction.

The invention will be more readily understood by a perusal of the following specification and by reference to the accompanying drawings, wherein an example of the invention is shown, and in which:

Figure 1 is a plan view of the joint, Fig. 2 is a side elevation of the same, with a portion shown in section,

Fig. 3 is a cross-sectional view on the line 3—3 of Fig. 2,

Fig. 4 is an isometric view of the end of one of the rails forming the joint, and

Fig. 5 is a similar view of the end of the other rail.

In the drawings the numeral 1 designates a tenon rail, and 2 a mortise rail. The adjacent end of each rail is formed with a laterally extending base portion 3 projecting somewhat beyond the base-flange 4 of each rail. These portions 3 register when

the rails are assembled. One of the portions 55 3 is cut back from the end of the rail 2; while the portion 3 of the rail 1 has a liberal extension projecting longitudinally from the web and head of said rail. The portions are surmounted by a longitudinal boss 60 6; while the end 7 of the web of each rail is increased in thickness to strengthen the same.

When the ends of the rails are brought together the overhanging web of the rail 65 2 rests on the boss of the rail 1. A web-lug or tenon 8 extends upward from the boss of the rail 1 and projects outward from the web. An upstanding stud 9 is provided on the outer extremity of the boss 6 over 70 the extension 5. The lug 8 is less in thickness than the web portion 7 so as to leave shoulders 10 at each side thereof.

The extremity of the web portion 7 of the rail 2 is formed with a socket 11 of such 75 size and shape as to snugly receive the lug 8, while the end of said portion abuts the shoulders 10. It will be seen that the parts are united in break-joint relation as the joint between the base portions 3 is off-set 80 some distance from the joint between the portions 7 and the load at the joint is sustained by the extension 5.

The lug 8 is provided with a slot 12 and the portion 7 of the rail 2 also has slots 12' 85 which register with the slot 12 when the parts are assembled. A bolt 13 is passed through the slots. The stud 9 engages in an elongated recess 14 in the bottom of the overhanging web portion of the rail 2. The 90 slots and the recess permit the rails to move longitudinally and independently of each other to such a degree as to allow for extreme contraction and expansion. It will be observed that even though the bolt 13 95 became detached the rails could not be separated unless they were moved vertically. It is apparent that rails formed with this joint may be readily and easily assembled and fastened in place.

What I claim, is:

In a rail joint, a tenon rail having an extended base portion, an upstanding stud on the extremity of the base portion of the tenon rail, an upright lug carried on the 105 extended base portion and integral with the web portion of the rail, in combination with a mortise rail having a base portion cut

back from its end and an overhanging web portion having a socket receiving the lug of the tenon rail, the base portion of the mortise rail abutting the extended base of 5 the tenon over which the web of the mortise rail rests, the web of the mortise rail abutting the web of the tenon rail on each side

of the lug, the mortise web and the tenon lug having registering slots, and a bolt passed through all the slots, the overhanging web portion having an elongated recess in its bottom receiving the stud. 10

In testimony whereof I affix my signature.
AARON W. GILMORE.
